J. A. Bradshaw

Throstle and Cap.

Patented Dec. 8, 1832.

Fig. 2.

7322X

Dec. 8. 1832

John A. Bradshaw, of Scarborough, Me.
Letters Patent.

The Schedule referred to in these Letters Patent and making part of the same containing a description in the words of the said John A. Bradshaw himself of his improvement in the machine for manufacturing cotton roving.

To all to whom these presents shall come: Be it known that I, John A. Bradshaw, of Scarborough, in the county of York, Commonwealth of Maine, chuse & have invented a new & useful improvement in a machine for the manufacturing cotton roving, & that the following is a full & exact description of the construction & operation of the said machine as invented or improved by me - A. A. S. Fig. 1. represents the frame of the said machine -

B. is a pulley on the main horizontal shaft, concealed in the drawing, & connected by a belt with the propelling power, on the end of said shaft is a gear, which moves the balance wheel C. on the said main shaft is a downing, also concealed as aforesaid connected by a belt with the down D. on the shaft in front - On the end of this shaft is a box gearing that moves the vertical down E. said down moves the spindle, F. by a belt passing round the pulley G. on said spindle - On the other end of the front shaft is the pinion H. which gears into & moves the wheel I another shaft of which is the worm J. which moves the wheel K. on the end of which shaft, is the heart wheel L. which plays against the disk wheel M. which gives a vertical motion to the spindle by means of the traverse N. N. N. - O. is a pulley connected by a belt P. with the main shaft first mentioned -

This pulley is on the end of the horizontal shaft Q. on the other end of which is a pinion geared into a stud wheel S. which so moves the rollers, & R. & R. as to give a progressive increase of velocity - Behind said rollers is the guide T. thro' which passes the cotton drawing as taken from the drawing frames - The cotton after passing between said rollers enters the friction guide U. to which is attached a weight, it then enters the flin V. thence passing thro' the guide U down one of its arms & thro' the guide X at the bottom, thence passing along the curved spring Y around a crook or projection & thence thro' the

7322X

perforation & near the end of said spring, thence around the bottom & which is fixed on the spindle & revolves with the same. The flie revolves on its bearing at 1. It is driven by the strength of the roving as it passes thro' the perforation in the spring. - Fig. H, is an enlarged representation of said flie & spring with its crook or projection & perforation, in which consists the new improvement & which spring &c. may be applied to a flie of any other form or shape. Its use is to give a slight degree of twist & greater consistency to the roving.
